UNITED STATES PATENT OFFICE.

WILLIAM L. PARKINSON, OF ASHLAND, OHIO.

VALVE.

1,025,827.

Specification of Letters Patent.

Patented May 7, 1912.

Application filed November 8, 1910. Serial No. 591,362.

To all whom it may concern:

Be it known that I, WILLIAM L. PARKINSON, a citizen of the United States, residing at Ashland, in the county of Ashland and 5 State of Ohio, have invented certain new and useful Improvements in Valves; and I do hereby declare the following to be a full, clear, and exact description of the invention, such as will enable others skilled 10 in the art to which it appertains to make and use the same.

My invention relates to new and useful improvements in valves and more particularly to that class adapted to be used in filling tanks and my object is to provide a pivoted valve which is adapted to swing over the end of the inlet pipe to stop the flow of water therefrom.

A further object is to provide means for 20 lowering the valve in position over the end of the inlet pipe and at the same time direct a pressure thereon.

A further object is to provide a bushing to reduce the pressure of the water when 25 entering the tank.

A further object is to so arrange the valve that the pressure of the water will be directed against the seat thereof, and, a further object is to provide a connection between the 30 inlet valve and the flush valve of the tank.

Other objects and advantages will be hereinafter set forth and pointed out in the specification.

In the accompanying drawings, which 35 form a part of this application, Figure 1 is an elevation partly in section of my improved valve. Fig. 2 is a plan view of the inlet pipe, and, Fig. 3 is a bottom plan view of the valve.

40 Referring to the drawings, in which similar reference numerals designate corresponding parts throughout the several views, 1 indicates the wall of the tank, which in this instance is used for closet 45 purposes, and 2 indicates a connection which projects through the bottom of the tank and terminates in a head 3 at its upper end, while the lower end thereof is attached to the usual form of water supply 50 pipe (not shown).

The upper end of the passage through the connection terminates in a nozzle 4, which is preferably tapered and in order to reduce the pressure of the water passing 55 through the connection, a tapered bushing 5, having its discharging end reduced in

size, is introduced into the nozzle and preferably projects beyond the end of the nozzle, although it may be flush therewith if so desired. The object in projecting the end of 60 the bushing beyond the nozzle is that the bushing may be reamed out or made larger in cases of low pressure and in some cases the bushing may be entirely dispensed with.

Extending upwardly from the head 3 65 is a standard 6, to which is pivoted the arm 7 of a valve 8, said valve being adapted to swing over the end of the nozzle. The lower face of the valve is provided with a cavity or seat 9, in which is preferably placed suitable packing 10, preferably of leather, so that when the valve is seated over the end of the bushing or nozzle a complete seal will be formed.

In order to control the movement of the 75 valve in accordance with the amount of water in the tank, a lever 11 is pivotally connected to the upper end of the standard 6 and the terminal 12 thereof projected over the valve and is connected to the valve by 80 a link 13 so that when the lever is swung upwardly or downwardly the valve will be accordingly lowered or raised.

The various pivotal connections between 85 the several parts are formed by means of cotter pins or split keys 14, which are preferably formed of brass to prevent corroding or rusting of the same and by using the cotter pins instead of bolts or rivets, the various parts of the valve construction can be 90 quickly taken down or assembled.

In order to prevent leakage around the connection 2 a gasket or similar device 15 is placed between the head and the bottom 95 of the tank and the head is drawn securely against the gasket by threading the exterior of the connection and introducing a nut 16 thereon, which nut jams against the bottom of the tank.

When the valve 8 is lifted from its seat 100 the cavity rests at an angle to the path of the flowing water and in view of the force of the water when entering the tank, any sand, sediment or other obstruction adhering to the packing or wall of the cavity will be removed. It will likewise be seen that in view of the cup shape of the cavity the water will be thrown downwardly toward the head after engaging the cavity. In order to permit a certain amount of water to 110 escape from the tank while the tank is being refilled, the head 3 is provided with a

substantially U-shaped port 17, that stem of the port adjacent the connection 2 being open, while that stem of the port farthest from the connection receives the threaded 5 end of a pipe 18, which extends from the head to a flush valve (not shown), and it will be readily seen that an additional amount of water will flow through the flush valve while the tank is being filled. It will 10 likewise be seen that the water will be directed into the open arm of the port under pressure in view of the angle of the valve proper when raised, as the water on leaving the cavity in the valve will be directed 15 toward the port. It will likewise be seen that this device can be very cheaply constructed and the parts thereof readily assembled and applied to use, and, it will likewise be seen that the valve will be thor- 20oughly cleaned of any sediment by the force of the water when entering the tank and that all of the wearing parts may be easily taken apart and renewed when necessary.

What I claim is:

25 In a tank valve construction the combination with a connection having an opening

therethrough, a head at the upper end of the connection and a standard at one side and integral with said head, said head having a substantially U-shaped port formed 30 therein in the side thereof opposite the standard, an overflow pipe leading from one stem of said port while the other end of said port is open, said pipe being opposite to and parallel with the standard, a valve 35 pivoted to the lower end of said standard and having a cavity adapted to fit over the upper end of said connection, a lever pivoted to the upper end of said standard, a link connecting the inner end of said lever 40 to the top of said valve, said link being positioned and working between the standard and overflow pipe, and a conical bushing in said connection to reduce the pressure of the water passing therethrough. 45

In testimony whereof I have signed my name to this specification in the presence of two subscribing witnesses.

WILLIAM L. PARKINSON.
